FILLING STATION UNIT

David Gregory Norris, Shreveport, La., assignor to The J. B. Beard Company, Inc., Shreveport, La., a corporation of Delaware

Application February 14, 1956, Serial No. 40,158

Term of patent 14 years

(Cl. D13—1)

Fig. 1.

Fig. 2.

Fig. 3.

Figure 1 is a side elevational view of a filling station unit showing my new design;

Figure 2 is a top plan view; and

Figure 3 is an end elevational view thereof.

The side of the design opposite that shown in Figure 1 is similar to the side shown.

I claim:

The ornamental design for a filling station unit, substantially as shown and described.
